UNITED STATES PATENT OFFICE.

EDWIN NORTON, OF NEW YORK, N. Y., AND JOHN G. HODGSON, OF MAYWOOD, ILLINOIS, ASSIGNORS TO AUTOMATIC VACUUM CANNING COMPANY, OF CHICAGO, ILLINOIS, A CORPORATION OF ILLINOIS.

APPARATUS FOR VACUUM-SEALING AND MECHANICALLY SEALING OR SEAMING SHEET-METAL CANS.

SPECIFICATION forming part of Letters Patent No. 782,203, dated February 7, 1905.

Application filed November 27, 1901. Serial No. 83,885.

To all whom it may concern:

Be it known that we, EDWIN NORTON, residing in the city of New York, in the county of New York and State of New York, and JOHN G. HODGSON, residing in Maywood, in the county of Cook and State of Illinois, citizens of the United States, have invented a new and useful Improvement in Machines or Apparatus for Vacuum-Sealing and Mechanically Sealing or Seaming Sheet-Metal Cans, of which the following is a specification.

Our invention relates to machines or apparatus for sealing and securing covers to sheet-metal cans or vessels by a combined vacuum or atmospheric pressure seal and a mechanical seal or seam uniting the seaming-flanges of the can and cover.

Heretofore in hermetically sealing and securing covers on and to sheet-metal cans or vessels by a combined vacuum or atmospheric pressure seal and a mechanical seal or seam formed by mechanically engaging or seaming together suitable flanges on the can and cover the can after being filled is placed in a vacuum chamber or receiver and the air exhausted therefrom and from the can and its contents, and then the cover is hermetically sealed and secured thereto by the vacuum or atmospheric pressure seal upon restoring atmospheric pressure to the receiver, after which the vacuumized and hermetically-sealed can is removed from the vacuum chamber or receiver machine and placed in a seaming-machine of any suitable kind—such as a roller seaming-machine, die seaming-machine, or other seaming-machine—and the flanges of the can and cover seamed together by a mechanical seal or seam which coöperates with the vacuum or atmospheric pressure seal in hermetically sealing and securing the cover on and to the body of the can or vessel and in compressing and holding compressed and confining the packing interposed between the can and cover, and heretofore two separate machines, requiring two separate handlings of the cans, have been employed for this purpose—first, a vacuum chamber or receiver machine for exhausting the air from the can and its contents and hermetically sealing and securing the cover thereon

by the vacuum or atmospheric pressure seal—such, for example, as that forming the subject of the E. Norton patent, No. 620,247, of February 28, 1899—and, second, a seaming-machine for forming the mechanical seal or seam—such, for example, as that forming the subject of the E. Norton patent, No. 610,558, of September 13, 1898, or the Heinig patent, No. 546,468, of September 17, 1895, or other well-known forms of seaming-machines.

The object of our invention is to provide a machine of a simple, efficient, and durable construction by means of which both the mechanical seal or seam and the vacuum or atmospheric pressure seal may be formed in one and the same machine, thus saving one handling of the cans and the time, expense, and labor incident thereto.

Our invention consists in the means we employ to practically accomplish this result—that is to say, it consists in the combination with a vacuum chamber or receiver, an exhaust mechanism therefor, and means for opening and closing the receiver with means within the receiver for forming the mechanical seal or seam between the seaming-flanges of the can and cover. The vacuum chamber or receiver may be of any suitable construction, and the seaming mechanism within the receiver may likewise also be of any suitable kind or construction, such as have heretofore been in use in the art, one or the other kind being employed according to the different styles or shapes of cans and covers or the flanges thereof to be operated upon, or according as the mechanical seal or seam to be formed between the seaming-flanges of the can and cover is of the friction or compression type, single-seam or crimp type, double-seam type, or other type familiar to those skilled in the art. The receiver which we prefer to employ, however, is preferably of a bell shape or with an open lower end, and closed by the reciprocating can-holder, plate, disk, door, or cover, upon which the can rests while being subjected to the operation of the can-seaming mechanism and by which the can is fed or moved within the receiver. The seaming die, device, or mechanism employed may be provided with

independently-movable dies, jaws, or rollers or not, according to the particular form or character of the can being operated upon and of seam designed to be formed between the 5 seaming-flanges of the can and cover.

In the accompanying drawings, forming a part of this specification, we have illustrated at Figures 1 to 6 the simplest form of machine known to us for practising our invention, the 10 same being a machine specially designed for operating upon a particular style of can and cover, in which the flanges thereof are adapted to be securely and tightly engaged, locked, and seamed together by forcibly driving the 15 seaming-flanges on the cover into engagement with the seaming-flange on the can by a straight downward movement of the seaming die, device, or mechanism and in which the seaming device or mechanism does not, therefore, require to be provided with the customary independently-movable parts, jaws, or rollers. In this particular construction of can, as will be seen from the drawings, the flexible and slightly - yielding or compressible seaming 20 flange or roll on the upper end of the can-body is tightly embraced and frictionally locked and engaged and firmly compressed by and between a pair of seaming-flanges on the cover, one of which has a slightly-inclined or wedging 25 lower portion and which form an annular groove or channel slightly smaller in cross-section than the seaming flange or roll on the can-body, so that when the flange or roll on the can-body is forced by great pressure into 30 the contracted annular channel formed by the parallel seaming-flanges on the cover and embraced thereby on both sides and compressed a tight and secure mechanical seal or seam is formed by and between the interengaging 35 seaming-flanges of can and cover, which securely holds the cover on the can, and compresses and confines and holds compressed and confined the packing between the can and cover, and in Fig. 10 we have shown our 40 invention as embodied in a machine for operation upon a crimped or single-seam can, as 45 illustrated in Fig. 9.

In the said drawings, Figs. 1 and 2 are side elevations of a machine embodying our invention looking from opposite sides. Fig. 3 is a rear elevation. Fig. 4 is a detailed central vertical section through the receiver. Fig. 6 is a detailed cross-section on line 6 6 of Fig. 1. Fig. 5 is a sectional view of the valve. 55 Figs. 7 and 8 are detail views showing the can before and after its cover is sealed and secured thereto by the combined vacuum-seal and mechanical seal or seam. Fig. 9 shows a crimp or single-seam can after being operated upon, and Fig. 10 a machine embodying our invention for vacuum-sealing and mechanically seaming the form of can shown in 60 Fig. 9.

In the drawings, A represents the frame of 65 the machine; B, the vacuum chamber or re-

ceiver; C, a reciprocating disk or plate which supports the can, moves it within the receiver, and serves also as a door or cover to close the open lower end of the receiver, and D is a reciprocating can-closing die, device, or seaming 70 mechanism within the receiver, having an operating stem or shaft d, extending through a stuffing-box B', with which the receiver is provided.

The vacuum chamber or receiver B connects 75 with an exhaust mechanism E, preferably a double-acting vacuum-pump, through the exhaust-pipe F, a closed tank or reservoir G being interposed to equalize the action of the pump and serve as the exhaust mechanism 80 should the pump be stopped temporarily. The exhaust-pipe F is furnished with a valve H, which is preferably a three-way valve, having ports h¹ h² h³, so that the communication between the vacuum-chamber and the exhaust mechanism may be closed and its communication with the air-inlet N' opened, as desired or required. A rubber or elastic packing-ring b is interposed between the receiver 85 B and the can-holding cover C of the receiver, said ring being preferably attached to the lower end of the receiver, which has a groove b² to receive it.

The receiver closing or covering and can holding or supporting plate or disk C is automatically operated or reciprocated as required to close the receiver and deliver the can within the receiver and hold the plate or disk C in coöperative relation with the seaming mechanism D by means of a cam C' on the cam-shaft K, operating a lever C², connected by a link C³ with a lever C⁴, which connects, through an adjustable link C⁵, with the stem C⁶ of the plate or cover C. The can closing or seaming die, mechanism, or device 90 D is automatically operated or reciprocated as required by means of a cam D' on the cam-shaft K, which engages a lever D², pivotally connected to a slide D³, which reciprocates in suitable guides D⁴ on the frame of the machine and to which slide the stem or shaft d of the can closing or seaming device or mechanism D is adjustably connected by the adjusting-screw d² and clamp or bearing d³, having bolts d⁴. The adjusting-screw d² slides 95 through a guide-arm a on the frame, having a clamp a' and bolts a². The valve H is automatically operated as required to connect the vacuum-chamber with the exhaust mechanism and to open the air communication to 100 relieve the vacuum and permit the cover C to separate from the receiver by means of the cam H' on the cam-shaft K through the connecting-link H² and lever H³. Motion is communicated to the cam-shaft K from the driving-shaft M through the connecting-gears m' and clutch m².

M' is the clutch-lever.

The receiver or vacuum-chamber B or its bracket B² is adjustably secured to the frame 105

A by a bolt B³. The guide C⁷, in which the stem C⁶ of the can support or receiver closing-plate C reciprocates, or its bracket C⁸ is adjustably secured to the frame A by a bolt 5 C⁹, and its position may be accurately adjusted by the adjusting-screw C¹⁰. The turnbuckle C¹¹ in the link C⁵ enables the can support or cover C to be accurately adjusted in respect to the receiver B.

10 N is a vacuum-gage connected with the receiver to indicate the degree of vacuum produced in the receiver by the exhaust mechanism.

In operation the exhaust mechanism or 15 pump E is continuously driven by its driving-pulley E' and is constantly acting. A can with its cover loosely in place thereon, as indicated in Fig. 7, being placed on the plate or disk C, the clutch-lever is moved, thus connecting the 20 cam-shaft K with the driving-shaft and causing the cam C' and connecting mechanism to move the can supporting and receiver closing-plate or disk C upward, closing the receiver and moving or feeding the can within 25 the receiver. The valve H is then turned by its operating-cam H', thus opening the communication between the constantly-acting exhaust mechanism E and the receiver B and causing the air to be exhausted from the receiver and from can and its contents through 30 the open mouth or end of the can. While the can is thus *in vacuo* in the receiver, the cam D', through the connecting mechanism, next operates the can-closing die, device, or mechanism 35 D and forcibly drives and compresses together the flanges on the can and cover and compressing the packing between the can and cover forms the mechanical seal or seam which rigidly and firmly locks and holds the cover 40 on and to the can. After the mechanical sealing or seaming operation is thus completed the further movement of the cam-shaft K causes the cam H' to close the exhaust-pipe and open the air-inlet N', thus restoring the 45 atmospheric pressure to the receiver and permitting the further movement of the cam-shaft to separate the can support or cover C from the receiver and withdraw the can therefrom, the can and its cover now being also 50 sealed and secured together by the vacuum or atmospheric pressure seal due to the vacuum within the can and the atmospheric pressure without.

As illustrated in Figs. 7 and 8 of the drawings, the can-body X is provided at its upper end with a flange or roll x, preferably formed on a separate piece or ring x' from the can-body itself, and the cover Y has an outer flange y and an inner flange y', having a slightly-inclined or wedging lower portion y², forming an annular groove or channel y³ between them slightly smaller in cross-section than the flange or roll x on the can-body and into which the flange or roll x on the can-body is forcibly 60 driven and compressed with a tight friction 65

or compression fit, thus firmly seaming and securing together the can and cover and compressing and holding compressed the packing V, which is interposed between the can X and the cover Y. As in this construction of can 70 the mechanical seal or seam is adapted to be formed by simply forcibly driving the cover home on the can, the seaming mechanism, die, or device D within the receiver, as indicated in the drawings, consists or may consist simply of a reciprocating seaming-die having no independently-movable parts. 75

In Fig. 9 a different form of cam is illustrated from that shown in Figs. 7 and 8, the same having the seaming-flanges of the can 80 and cover united by a crimp or single seam, and the seaming mechanism D (shown in Fig. 10) for operation upon this form of can has independently-movable seaming or crimping rollers d⁵, and the stem or shaft d of the 85 seaming mechanism is provided with a pulley for rotating the same, this being a well-known form of seaming mechanism for seaming cans of the style illustrated in Fig. 9. This seaming mechanism or device D (shown in Fig. 10) 90 has a sliding block d⁶, splined to the seaming-head and rotating with it, furnished with springs d⁷ and has ball-bearings d⁸ between it and the disk d⁹, which bears against the can-head, so that when the seaming device D 95 descends its non-rotating head or disk d⁹ will by sliding the block d⁶ compress the springs d⁷ and throw the crimping-rolls d⁵ in against the outer flange of the can-head and turn the same inward and firmly compress together the 100 seaming-flanges of the can head and body and form a seam.

By the use of either or each of the following phrases "seaming mechanism," "seaming device," "means for seaming together the 105 flanges of the can and cover," "means for seaming together into a seam the flanges of the can and cover" we include and mean to include as one form thereof the die-seaming device or mechanism D, as shown in the principal form of our invention illustrated in Figs. 1 to 6 of the drawings and the particular construction of which is detailed in Fig. 4 of the drawings, and we desire it to be distinctly understood, as we have hereinbefore stated, that 110 our invention is not limited to the use of the particular form of seaming device or seaming mechanism illustrated in Fig. 10, but includes the form of seaming device or seaming mechanism shown in Fig. 4. 115

While we are the first to combine together a receiver and a seaming mechanism inside the receiver and are the first and original inventors of this broad and generic combination, we wish it to be distinctly understood 120 that we do not claim to be the first to combine and use inside a receiver the particular form or kind of seaming mechanism shown in the R. A. Hall patent, No. 676,229, of June 11, 1901, and "operating upon the edge of the 130

flange of the cover to bend the same underneath the shoulder on the can to form a joint between the two," such being the invention of said Hall.

5 We claim—

1. The combination with a vacuum-chamber or receiver having an open lower end of an exhaust mechanism, a reciprocating can holding and receiver closing-plate for moving the can within the receiver and closing it, mechanism automatically operating said plate, an air-inlet, a valve for opening and closing said air-inlet, and mechanism for automatically operating said valve, substantially as specified. 70
- 10 2. The combination with a vacuum-chamber or receiver having an open lower end of an exhaust mechanism, a reciprocating can holding and receiver closing-plate for moving the can within the receiver and closing it, mechanism automatically operating said plate, an air-inlet, a valve for opening and closing said air-inlet, and mechanism for automatically operating said valve, said valve operating mechanism serving to open said air-inlet and 75 relieve the vacuum in the receiver before said can-holder plate-operating mechanism withdraws it from the receiver, substantially as specified. 80
- 15 3. The combination with a vacuum-chamber or receiver, of a reciprocating can holding and receiver closing-plate for moving the can within and closing the receiver, and automatic mechanism for operating said plate, substantially as specified. 85
- 20 4. The combination with a vacuum-chamber or receiver, of a reciprocating can holding and receiver closing-plate for moving the can within and closing the receiver, automatic mechanism for operating said plate, and a can- 90 seaming mechanism within the receiver for forming a mechanical seam between the flanges of the can and cover, and means for automatically operating said seaming mechanism, substantially as specified. 95
- 25 5. The combination with a receiver of a can-seaming mechanism within the receiver for folding or compressing into a seam the flanges of the can and cover, substantially as specified. 100
- 30 6. The combination with a receiver of a reciprocating can-holder for closing the receiver and supporting the can therein, and a seaming device within the receiver, substantially as specified. 105
- 35 7. The combination with a receiver of a reciprocating can-holder and a movable seaming device within the receiver, substantially as specified. 110
- 40 8. The combination with a receiver of an exhaust mechanism, a reciprocating can-holder closing the receiver, and a can-closing mechanism within the receiver causing the flanges of can and cover to form a tight mechanical seam, substantially as specified. 115
- 45 9. The combination with a receiver having an open lower end of an exhaust mechanism, a reciprocating plate closing the receiver and moving the can within the receiver, a can-seaming mechanism within the receiver, and a valve to open an air-inlet to the receiver, substantially as specified. 120
- 50 10. The combination with a receiver having an open lower end of an exhaust mechanism, a reciprocating plate closing the receiver and moving the can within the receiver, a can-seaming mechanism within the receiver, and a valve to open an air-inlet to the receiver, and means for automatically opening said valve after the seaming operation is completed, substantially as specified. 125
- 55 11. The combination with a receiver having a grooved lower end furnished with a sealing-ring of an exhaust mechanism, a reciprocating can-holder closing the receiver, and a can-closing mechanism within the receiver causing the flanges of can and cover to form a tight mechanical seam, substantially as specified. 130
- 60 12. The combination with a receiver of an exhaust mechanism, a reciprocating can-holder closing the receiver, a seaming mechanism within the receiver, a valve for closing an air-inlet to the receiver, means for operating the seaming mechanism and means for automatically opening the valve when the seaming operation is completed, substantially as specified. 135
- 65 13. The combination with a receiver having an open lower end of a reciprocating plate closing the receiver and supporting the can, a sealing-ring between the receiver and said plate, and a seaming mechanism within the receiver, substantially as specified. 140
- 70 14. The combination with a receiver or vacuum-chamber of an exhaust mechanism, reciprocating means for closing the receiver and moving the can within the receiver, and means for seaming together the flanges of the can and cover within the receiver, substantially as specified. 145
- 75 15. The combination with a receiver having an open lower end of a reciprocating plate closing the receiver and supporting the can, an exhaust mechanism, a valve opening and closing an air-inlet to the receiver, a seaming device or mechanism within the receiver, and a cam-shaft having cams for automatically operating said plate, said can-seaming mechanism and said valve, substantially as specified. 150
- 80 16. The combination with a receiver having an open lower end of a reciprocating plate closing the receiver and supporting the can, and means within the receiver for seaming together the flanges of the can and cover, substantially as specified. 155
- 85 17. The combination with a receiver having an open lower end provided with a channel to receive a packing, a packing in said channel, a reciprocating plate for closing the receiver and supporting the can within the receiver, substantially as specified. 160
- 90 18. The combination with a receiver having an open lower end of a reciprocating plate closing the receiver and supporting the can, a can-seaming mechanism within the receiver, and a valve to open an air-inlet to the receiver, substantially as specified. 165
- 95 19. The combination with a receiver having an open lower end of a reciprocating plate closing the receiver and supporting the can, a can-seaming mechanism within the receiver, and a valve to open an air-inlet to the receiver, substantially as specified. 170
- 100 20. The combination with a receiver having an open lower end of a reciprocating plate closing the receiver and supporting the can, a can-seaming mechanism within the receiver, and a valve to open an air-inlet to the receiver, substantially as specified. 175
- 105 21. The combination with a receiver having an open lower end of a reciprocating plate closing the receiver and supporting the can, a can-seaming mechanism within the receiver, and a valve to open an air-inlet to the receiver, substantially as specified. 180
- 110 22. The combination with a receiver having an open lower end of a reciprocating plate closing the receiver and supporting the can, a can-seaming mechanism within the receiver, and a valve to open an air-inlet to the receiver, substantially as specified. 185
- 115 23. The combination with a receiver having an open lower end of a reciprocating plate closing the receiver and supporting the can, a can-seaming mechanism within the receiver, and a valve to open an air-inlet to the receiver, substantially as specified. 190
- 120 24. The combination with a receiver having an open lower end of a reciprocating plate closing the receiver and supporting the can, a can-seaming mechanism within the receiver, and a valve to open an air-inlet to the receiver, substantially as specified. 195
- 125 25. The combination with a receiver having an open lower end of a reciprocating plate closing the receiver and supporting the can, a can-seaming mechanism within the receiver, and a valve to open an air-inlet to the receiver, substantially as specified. 200
- 130 26. The combination with a receiver having an open lower end of a reciprocating plate closing the receiver and supporting the can, a can-seaming mechanism within the receiver, and a valve to open an air-inlet to the receiver, substantially as specified. 205

18. In a machine for vacuum-sealing and mechanically sealing sheet-metal cans, the combination with a receiver of means for supporting the can within the receiver and means for seaming together into a seam the flanges of the can and cover within the receiver, substantially as specified. 65
19. In a machine for vacuum-sealing and mechanically sealing cans, the combination 10 with a receiver having an open lower end, of a reciprocating can-carrier for moving the can within the receiver, and closing the receiver, a sealing-ring between the receiver and can-carrier, and means for mechanically seaming 15 together the flanges of the can and cover within the receiver, substantially as specified. 70
20. The combination with a receiver of an exhaust mechanism, a reciprocating can-holder closing the receiver, and a seaming mechanism 20 within the receiver, substantially as specified. 75
21. The combination with a receiver of an exhaust mechanism, a plate closing the receiver and supporting the can therein, and a seaming mechanism within the receiver, substantially as specified. 80
22. The combination with a receiver of an exhaust mechanism, a reciprocating plate for closing the receiver and supporting the can, means for operating said plate, a seaming 30 mechanism within the receiver and means for operating the seaming mechanism, substantially as specified. 85
23. The combination with a receiver of an exhaust mechanism, a reciprocating plate for closing the receiver and supporting the can, means for operating said plate, a seaming mechanism within the receiver, and means for operating the seaming mechanism, a valve for opening an air-inlet to the receiver, and means 35 for automatically operating said valve, substantially as specified. 90
24. The combination with a receiver or vacuum-chamber, of a plate or door for closing the chamber, an exhaust mechanism, a can-seaming mechanism within the receiver to fold or compress into a seam the flanges of the can and cover, and means for opening an air-inlet to the chamber after the seaming operation is completed and before the door or plate 45 is opened, substantially as specified. 95
25. The combination with a receiver of means within the receiver for seaming together into a seam the flanges of the can and cover, substantially as specified. 100
26. The combination with a receiver of an exhaust mechanism and means within the receiver for seaming together into a seam the flanges of the can and cover, substantially as specified. 105
27. The combination with a receiver of means within the receiver for seaming together the flanges of the can and cover, means for automatically opening and closing the receiver and moving the cans therein, and means for auto- 110
- matically operating the seaming mechanism, substantially as specified. 115
28. The combination with a receiver B, of a seaming device D in the receiver, and provided with an independently-movable rotary seaming-roller d², carried thereby and co-operating therewith, and a movable plate C, and means for operating the same, substantially as specified. 120
29. The combination with a vacuum-chamber or receiver having an open lower end of an exhaust mechanism, a reciprocating can-holding and receiver-closing plate for moving the can within the receiver and closing it, mechanism for automatically operating said plate, an air-inlet, a valve for opening and closing 125 said air-inlet, mechanism for automatically operating said valve, a reciprocating can-closing device within the receiver, and mechanism for automatically operating said device, substantially as specified. 130
30. The combination with a vacuum-chamber or receiver having an open lower end of an exhaust mechanism, a reciprocating can holding and receiver closing-plate for moving the can within the receiver and closing it, mechanism automatically operating said plate, an air-inlet, a valve for opening and closing said air-inlet, mechanism for automatically operating said valve, said valve-operating mechanism serving to open said air-inlet and relieve the vacuum in the receiver before said can-holder plate-operating mechanism withdraws it from the receiver, a reciprocating can-closing device within the receiver, and mechanism for automatically operating said device, substantially as specified. 135
31. The combination with a vacuum-chamber or receiver, of a reciprocating can holding and receiver closing-plate for moving the can within and closing the receiver, automatic mechanism for operating said plate, a reciprocating can-closing device within the receiver, and mechanism for automatically operating said device, substantially as specified. 140
32. The combination with a vacuum-chamber or receiver, of a reciprocating can holding and receiver closing-plate for moving the can within and closing the receiver, a reciprocating device within the receiver for forcing the cover on the can, means for automatically operating said can holding and receiver closing-plate and said reciprocating device within the receiver to first close the receiver and then force the cover on the can, substantially as specified. 145
33. The combination with a vacuum-chamber or receiver, of a reciprocating can holding and receiver closing-plate for moving the can within and closing the receiver, a reciprocating device within the receiver for forcing the cover on the can, an exhaust mechanism, a valve controlling the communication between the receiver and exhaust mechanism, 150

and means for automatically operating said parts to first move the can within the receiver and close the receiver, then exhaust the air from the receiver and can and then force the 5 cover on the can, substantially as specified.

34. The combination with a vacuum-chamber or receiver of a reciprocating can holding and receiver closing-plate for moving the can within and closing the receiver, a reciprocating device within the receiver for forcing the cover on the can an exhaust mechanism, a valve controlling the communication between the receiver and the exhaust mechanism, means for operating said reciprocating can holding and receiver closing-plate, and 10 15

means for automatically operating said valve to open the communication between said exhaust mechanism and said receiver after the receiver is closed by said reciprocating can holding and receiver closing-plate, substantially as specified. 20
